(57) **CLAIM**

The ornamental design for a push pin pliers, as shown and described.

DESCRIPTION

FIG. 1 is a top plan view of the primary embodiment of the push pin pliers;

FIG. 2 is a right side elevation view thereof;

FIG. 3 is a bottom plan view thereof;

FIG. 4 is a left side elevation view thereof;

FIG. 5 is a rear elevation view thereof;

FIG. 6 is a front elevation view thereof;

FIG. 7 is a right side elevation view of an alternative embodiment of the push pin pliers and the left side elevation view is identical and reversed;

FIG. 8 is a top plan view thereof and the bottom plan view is identical;

FIG. 9 is a front elevation view thereof; and,

FIG. 10 is a rear elevation view thereof.
